Attorney

UNITED STATES PATENT OFFICE

THOMAS G. CRAIGHEAD, OF SEATTLE, WASHINGTON

NECKTIE

Application filed November 21, 1930. Serial No. 497,277.

This invention relates to improvements in neck wear, and more particularly to a necktie.

The principal object of the invention is to provide an attractive tie which may be quickly applied to a collar and quickly removed therefrom, and which requires no part of the tie to encircle the neck of the wearer, thus insuring a tie which is at all times properly looped and fashioned when it comes into the hands of the user in the first place.

It often occurs that a necktie, for example what is commonly known as a four-in-hand, is not always properly looped and adjusted, especially when the wearer is in a hurry, in positioning the tie, and it also often happens that a tie properly folded and adjusted in the beginning becomes out of place with respect to the collar.

Many persons are particularly unskilled in the tying of neckties and have difficulty in looping the tie in proper form. By the use of my improved tie, these disadvantages are all obviated. The tie is secured in place with a minimum of effort and time and does not in any way soil or muss the collar as a person is likely to do in tying a four-in-hand tie.

The invention is illustrated in the accompanying drawings, in which:—

Figure 1 is a front view of the tie in position.

Figure 2 is a back view of the tie alone.

Figure 3 is a sectional view on the line 3—3 of Figure 1.

The necktie, which is shown as a straight narrow tie for purposes of convenience, may be made in any form and of any shape. It is shown made up of a body portion 1 having a band portion 2 which encircles the body portion near the top. The band eliminates the necessity of tying the body portion of the tie and the consequent pulling out of shape.

The tie is formed by folding the body portion 1 at substantially midpoints and allowing the free ends to overlie one another so that the tie will at all times lie flat and even. To form the semblance of a knot, the band 2 is passed around the body portion adjacent the folded end and secured there. Between the band and the folded end of the tie and on the

section next to the wearer is a buttonhole 3, by means of which the tie may be fastened to the ordinary collar button 4. The tie is shown with a collar 5 in Figure 1, where it may be easily seen that the securing of the tie would not muss or dirty the collar.

From the foregoing description, it is easily seen that the tie herein described may be made in any form or with any shape tie, the principal function of the invention being to provide a tie that will retain its shape, lie flat and which will be easy to affix and take off. A tie such as above described could be made from less material, as the knot structure of the tie is usually about three times the length of tie necessary to encircle said tie as the band 3 does.

I claim:—

A necktie including a body portion formed from a length of cloth folded at its middle and arranged so that its sections lie flat, one against the other, said rear section of the body portion having a buttonhole formed therein adjacent the fold, and a band encircling the two sections and secured thereto to imitate a knot formed therein.

In testimony whereof I affix my signature.

THOMAS G. CRAIGHEAD.
